UNITED STATES PATENT OFFICE.

WILLIAM A. TORPEY, OF CHICAGO, ILLINOIS.

CLEANING DEVICE FOR TUBULAR BOILERS.

1,286,451.

Specification of Letters Patent.

Patented Dec. 3, 1918.

Application filed March 6, 1917. Serial No. 152,728.

To all whom it may concern:

Be it known that I, WILLIAM A. TORPEY, a citizen of the United States, and a resident of the city of Chicago, county of Cook, and 5 State of Illinois, have invented certain new and useful Improvements in Cleaning Devices for Tubular Boilers, of which the following is a specification.

My invention relates to improvements in 10 cleaning devices for tubular boilers, and has for its object the production of a device of this character through the medium of which the interior of a tubular boiler may be readily and expeditiously cleaned.

15 A further object is the production of a device of this character which will be of durable and economical construction, one which may be readily and easily inserted into and removed from a boiler, and further, 20 one which will be highly efficient in use.

Other objects will appear hereinafter.

The invention consists in the combinations and arrangements of parts hereinafter described and claimed.

25 The invention will be best understood by reference to the accompanying drawings forming a part of this specification, and in which,

Figure 1 is a longitudinal section through 30 a conventional form of a tubular boiler in which is arranged a cleaning device, embodying the invention.

Fig. 2 is a section taken on line $\alpha-\alpha$ of Fig. 1,

35 Fig. 3 is a central vertical section of a portion of the device, and

Fig. 4 is a sectional view of another form of the invention.

One form of construction as illustrated in 40 the drawings comprises a shoe or support 1 which consists primarily of two spaced parallel members adapted, when the device is in use, to engage with and ride upon the bottom of the boiler A in conjunction with 45 which the device is employed. Said side members of the shoe 1 are rigidly connected by means of integral cross bars 2 and 3, a pipe 4 arranged in said shoe being anchored at one end in the cross piece 2. Said pipe 50 4 is adapted for connection with a fluid supply pipe 5, a suitable connecting member 6 being employed to effect such connection. The pipe 5 is of a sectional nature in order to permit of the collapse of the device into 55 a small space, when not in use, and further

in order to adapt the device for use in connection with boilers of any size or length.

Arising from the shoe 1 is an elongated tubular spraying element 7 adapted, when in use, to engage between the tubes B of 60 the boiler in connection with which the device is employed. The spraying element 7 is formed with spaced laterally discharge openings 7' and a terminal perforated discharge nozzle 7".

65 The lower end of spraying element 7 is rigidly secured in a collar or holder 8 having trunnions 9 which pivotally engage in the opposite sides of shoe 1. The arrangement is such that a connection between the 70 spraying device and the shoe is effected which permits of pivotal movement of said element in a vertical longitudinal plane. To hold the spraying element in vertical or operative position, a cross bar 10 is provided 75 which connects the upper ends of the side members of shoe 1 against which the spraying element is adapted to engage, a strap 11 pivotally connected at 12 with one side of shoe 1 being adapted to coöperate with the 80 bar 10 in embracing the lower end of the spraying element to hold the same rigid in vertical position. A thumb nut 13 is adapted for releasable engagement with the free end of strap 11 in locking the latter in 85 operative position.

When the spraying element 7 is in vertical or operative position, the lower end thereof is adapted for connection with the upwardly turned forward end of pipe 4. This connection is effected by means of a threaded union 14 adapted for engagement with the reduced threaded lower end of collar 8, the lower end of said union being provided with an inwardly projecting annular flange 95 which is adapted for engagement with an outwardly projecting flange provided upon a sleeve 14' which embraces the upwardly projecting end of pipe 4. To insure an absolute tight connection a packing ring or washer may be inserted between the parts as seen. The arrangement is such that, when the union 14 is disengaged from the collar 8, the forward end of pipe 4 will spring 100 downwardly in order to allow for clearance of the lower end of member 7 when the latter is rocked to horizontal or inoperative position, as seen in dotted lines in Fig. 3. To permit of ready access being gained to the union 14, the opposite sides of shoe 1 105

are provided with openings 15 as clearly seen in Figs. 1 and 2.

To further securely brace the spraying element when in vertical or operative position, a brace rod 16 is provided, pivotally connected at its upper end as at 17 with said spraying element, the lower end of said brace rod being releasably connected with the cross bar 2 of the shoe 1 by means of a removable pin 18. When it is desired to swing the spraying element downwardly to inoperative position, the pin 18 is removed in order to release the rod 16.

In using the device the same is inserted 15 through the opening C usually provided at one end of a conventional boiler. In this insertion the spraying element 7 is of course in lowered position, as shown in dotted lines in Fig. 3. After insertion of the device, the 20 spraying element 7 is swung to vertical position and locked by means of strap 11 and brace rod 16. This having been done the connection of the lower end of the spraying device with the pipe 4 is readily and easily 25 effected through manipulation of the union 14. Cleansing fluid is then supplied through the pipe 5, the fluid thus applied being sprayed from the element 7 through the openings 7' and nozzle 7'', which results in 30 a thorough cleansing of the interior of the boiler and the exterior surfaces of the tubes B. The supply pipe 5 is used to move the device longitudinally of the boiler in the 35 cleansing operation. In the removal of the device from the boiler after the cleansing operation, the spraying element is of course released and rocked to its lower or horizontal position.

If desired the entire construction may be 40 greatly simplified by forming the lower end of the spraying element 7 integral with a shoe or support 1', in which is formed a passage 4 adapted for connection with the pipe 5, a union 6' being employed in the 45 connection. The shoe 1' is very short so as to permit of insertion of the same through the opening C of the boiler. In other words the length of said shoe will be less than the diameter of said opening. In either form the 50 ends of the shoe are rounded so as to permit of the same readily riding over all obstructions such as rivet heads, overlapping ends of sheet metal wall sections and the like, when the device is moved longitudinally in 55 the boiler.

While I have illustrated and described the preferred forms of construction for carrying my invention into effect, these are capable of variations and modifications without 60 parting from the spirit of the invention. I, therefore, do not wish to be limited to the precise details of construction set forth, but desire to avail myself of such variations and modifications as come within the scope of 65 the appended claims.

Having described my invention what I claim as new and desire to secure by Letters Patent is:

1. A device for washing the interior of tubular boilers comprising an upright tubular spraying element adapted for insertion into a boiler between the tubes thereof; a supporting shoe from which said spraying element projects; a pivotal connection between said shoe and said element permitting of swinging of the latter in a vertical plane extending longitudinally of the tubes of the boiler in which the device is used; means for locking said element in vertical position; a cleansing fluid supply pipe having one end secured to said shoe; and a releasable connection between said pipe end and said spraying element, substantially as described. 75

2. A device for washing the interior of tubular boilers comprising an upright tubular spraying element adapted for insertion into a boiler between the tubes thereof; a supporting shoe from which said spraying element projects; a pivotal connection between said shoe and said element permitting of swinging of the latter in a vertical plane extending longitudinally of the tubes of the boiler in which the device is used; means for locking said element in vertical position; a cleansing fluid supply pipe having one end secured to said shoe; and a releasable connection between said pipe end and said spraying element, substantially as described. 80

3. A device for washing the interior of tubular boilers comprising an upright tubular spraying element adapted for insertion into a boiler between the tubes thereof; a supporting shoe from which said spraying element projects; a pivotal connection between said shoe and said element permitting of swinging of the latter in a vertical plane 105 extending longitudinally of the tubes of the boiler in which the device is used; means for locking said element in vertical position; a cleansing fluid supply pipe having one end secured to said shoe; and a releasable connection between said pipe end and said spraying element, said connection comprising a threaded union adapted to releasably engage with and draw the parts together to 110 form a tight connection between the same, substantially as described. 115

4. A device for washing the interior of tubular boilers comprising an upright tubular spraying element adapted for insertion into a boiler between the tubes thereof; a supporting shoe from which said spraying element projects; a pivotal connection between said shoe and said element permitting 125

of swinging of the latter in a vertical plane extending longitudinally of the tubes of the boiler in which the device is used; and means for locking said element in vertical position, 5 said means comprising a strap pivotally connected with said shoe and adapted to releasably engage with said element, substantially as described.

In testimony whereof I have signed my name to this specification in the presence of 10 two subscribing witnesses.

WILLIAM A. TORPEY.
